DESIGN FOR A COMBINED ASH TRAY AND SAFETY MATCH HOLDER

Michael Mayer, Cleveland, Ohio

Application April 16, 1943, Serial No. 109,981

Term of patent 14 years

To all whom it may concern:

Be it known that I, Michael Mayer, a citizen of the United States, residing at Cleveland, in the county of Cuyahoga and State of Ohio, have invented a new, original, and ornamental Design for a Combined Ash Tray and Safety Match Holder, of which the following is a specification, reference being had to the accompanying drawing, forming a part thereof, in which

Fig. 1 is a perspective view of a combined ash tray and safety match holder embodying my new design;

Fig. 2 is a side elevation of the same; and

Fig. 3 is an end view of the same looking toward the left of Fig. 2.

I claim:

The ornamental design for a combined ash tray and safety match holder, substantially as shown.

MICHAEL MAYER,
